UNITED STATES PATENT OFFICE.

GOTTFRIED BUCHERT, OF LAURAHUTTE, GERMANY.

APPARATUS FOR REMOVING SUPERFLUOUS METAL FROM METAL-COATED BODIES.

1,034,687.

Specification of Letters Patent. Patented Aug. 6, 1912.

Application filed February 24, 1911. Serial No. 810,564.

To all whom it may concern:

Be it known that I, GOTTFRIED BUCHERT, a subject of the King of Bavaria, and residing at Laurahutte, Germany, have invented a new and Improved Apparatus for Removing Superfluous Metal from Metal-Coated Bodies, of which the following is a specification.

This invention relates to a new and improved apparatus for removing superfluous metal from metal coated bodies, the invention being particularly adapted for removing the superfluous metal from the interior of coated tubes or similar hollow bodies, such as zinc-coated iron tubes.

The invention is applicable to the coating of tubes or tube like bodies of various cross sections, which can be treated all by the same apparatus without requiring a readjustment of the same.

In the accompanying drawing: Figure 1 is a longitudinal section of an apparatus embodying my invention; Fig. 2 an end view partly in section thereof; Fig. 3 a plan; Fig. 4 a side view of part of the tube conveying means; Fig. 5 a plan thereof; Fig. 6 a detail of the knocking out device; Fig. 7 a cross section thereof, and Fig. 8 a detail of a modification of the knocking out device.

The apparatus comprises essentially a frame 1 supported on casters and carrying a pair of horizontal rails 9, which at their forward end connect with a pair of inclined rails 8, the latter being secured at their lower ends to a bracket 2 of the frame. Above each rail pair 9, 8 extends the upper run of an endless conveyer chain 7 passing over pulleys 7^a, 7^b, 7^c and provided with aligned tappets 7^d, the chains being driven in suitable manner (not shown). Tappets 7^d are adapted to removably engage a transversely disposed rod 23, from which a tong 24 is suspended, so that the tong is taken along by the chains. Tong 24 is adapted to grasp the upper end of a tube or other body, 5 from the interior of which the superfluous coating metal is to be removed, said tube being received by the tong at the bottom of the inclined rails 8. Here there is arranged in front of the apparatus a vessel 4 containing the zinc or other coating bath, and provided with a wiper 6, through which tube 5 is drawn by the tong. Below the forward portion of the frame, i. e. below the entire length of the inclined rails 8

and below portions of the horizontal rails 9, there is arranged a tray 11 adapted to receive the superfluous coating metal knocked out of the interior of tube 5. Tray 11 is provided near its top with a plurality of spaced horizontal grate bars 10, constituting tapping devices. As tube 5 is drawn over the tray by tong 24, its freely suspended lower end will strike the successive grate bars, so that the superfluous coating metal is loosened and may readily fall out of the tube into said tray.

Upon rails 9 travels a carriage 17 adapted to be taken along by rod 23 and connected by chain 16 running under pulleys 16^a to the forward end of a platform 14 oscillable on fulcrum 14^a of the machine frame. This platform is balanced by counterweight 14^b as to normally assume a horizontal position, but is by carriage 17 and chain 16 swung into an inclined position during the forward travel of the carriage, so as to be ready for the reception of tube 5. Near the ends of rails 9, there is provided at the side of one of the chains 7, an inclined abutment 18 adapted to be engaged by rod 23. When the rod strikes this abutment, it will be so tilted during the further advance of the chain, that it becomes dislodged from tappets 7^d and thus becomes released from the chain, while carriage 17 becomes simultaneously released from the rod. The carriage thus liberated will cease to exercise a pull on platform 14, while the uncoupling of rod 23 from chains 7 will cause tong 24 to release tube 5. The tube which had previously been laid by the tongs against platform 14 will now be swung into a horizontal position. Rod 23 will drop together with tong 24 through a chute 21 upon an endless conveyer 22. The latter runs along the side of the machine and carries the rod and tong back within reach of the starting point 6.

On that side of the machine frame opposite to conveyer 22, there is arranged a water tank 15. Within tank 15 is mounted a rotary shaft 19 provided with a plurality of wings 20, that are adapted to dip into the tank and grasp the tube which had been rolled from the platform 14 into the tank. The tube after being properly cooled will thus be lifted by the wings out of the tank and thrown into a cart or other receiver.

The operation of the machine will be apparent from the above description. After tube 5 has been drawn by the tong 24 out

of the coating bath 4, it will be carried in a freely suspended state over grate 10, so as to successively strike the grate bars with its lower end. Owing to the substantial weight of the tube and to the inclined position of the latter, these rapidly following blows will cause the surplus zinc remaining in the tube to be loosened up and to drop freely out of the same into tray 11. In this way the interior of the tube is cleaned out in a simple manner, and waste of coating metal is avoided. The tube emptied as described is placed by tongs 24 against the platform 14, while the latter is held in an inclined position by carriage 17. When bar 23 carrying tongs 24 strikes abutment 18, the pull on the platform ceases and the latter is swung back into a horizontal position. The tube 5 is now rolled sidewise off the platform 20 into cooling tank 15 from which it is ultimately ejected by wings 20.

Fig. 8 illustrates a modification of the knocking out mechanism. Here grate 10 is supplanted by a rotating shaft 13 carrying beaters 12 that are adapted to successively strike the sides of the tube to be cleaned, the latter being suspended in a vertical position.

I claim:

- 30 1. A device of the character described, comprising a tapping device, a tiltable platform, and means for carrying a hollow coated body into contact with said tapping device and upon the platform.
- 35 2. A device of the character described,

comprising a tapping device, a chain conveyer, a tong carried thereby and adapted to drag a hollow coated body over the tapping device, and means for releasing the tong from said conveyer.

40

3. A device of the character described, comprising a tapping device, a pair of chains, a rod removably engaging the chains, a tong suspended from the rod and adapted to drag a hollow coated body over 45 the tapping device, and means for releasing the rod from the chains.

4. A device of the character described, comprising a tapping device, a chain conveyer, a tong carried thereby and adapted to 50 drag a hollow body over the tapping device, means for releasing the tong from the conveyer, and a tiltable platform arranged back of the tapping device.

5. A device of the character described, 55 comprising a tapping device, a pair of chains, a rod removably engaging the chains, a tong suspended from the rod, a carriage operated by the rod, means for disengaging the rod from the chains, and a tiltable 60 platform operably connected to the carriage.

It witness whereof I have hereunto signed my name in the presence of two subscribing witnesses.

GOTTFRIED BUCHERT.
